APRON FOR A BATHTUB

Milton D. Schiffman, Chicago, Ill.

Application October 21, 1955, Serial No. 38,517

Term of patent 7 years

(Cl. D4—4)

Fig. 1 is a perspective view of an apron for a bathtub showing my new design, same being shown in solid lines.

Fig. 2 is a top plan view of said apron.

Fig. 3 is a fragmentary elevational view taken from the right of Figure 1.

Fig. 4 is a sectional view taken on lines 4—4 of Fig. 1.

The bathtub shown by means of broken lines is only disclosed for purpose of illustration.

I claim:

The ornamental design for an apron for a bathtub, as shown and described.
